STOVEPIPE FASTENER

George Lafever, Kelso, Wash.

Application March 3, 1939, Serial No. 259,631

3 Claims. (Cl. 126—318)

This invention relates generally to heating appliances, and particularly to a stovepipe fastener.

The main object of this invention is to construct a fastener for stovepipes which will prevent them from being accidentally withdrawn from a flue opening.

The second object is to construct the device in a manner that it will be inexpensive to make, easy to apply and remove and not affected by the corrosive action of the gases and heat within the flue.

These and other objects are accomplished in the manner set forth in the following specification as illustrated in the accompanying drawing, 15 in which:

Fig. 1 is a fragmentary view showing the preferred form of the device applied to a flue and showing the flue and the device itself cut away in cross-section.

20 Fig. 2 is a horizontal section through the device showing same in a locked position in dotted lines and in an unlocked position in full lines.

Fig. 3 is an end elevation of Fig. 2.

25 Fig. 4 is a fragmentary side elevation of the latching member taken along the line 4—4 in Fig. 2.

Similar numerals refer to similar parts throughout the several views.

Referring in detail to the drawing, there is 30 shown a flue 10 having the usual refractory thimble 11 which forms a part of the flue. The device itself consists of a length of stovepipe 12 having the usual bead 13 formed a short distance from the end 14; the bead 13 stops against the thimble 11.

On the inside of the pipe 12 is secured a yieldable arm 15 to which is hingedly attached a rigid bar 16 having a hook 17 formed on the end thereof. Also attached to the pipe 12 and opposite the arm 15 is a yieldable latch 18 having a hole 19

formed therein adapted to receive the point 20 of the hook 17.

The operation of this form of the device is as follows:

To insert the pipe 12 into the thimble 11, it is 5 only necessary to have the parts in the position shown in full lines in Fig. 2 and to push the pipe 12 into the thimble 11 and then to reach in and insert the point 20 of the hook 17 into the hole 19 causing the members 15 and 18 to spread outwardly to the position shown in dotted lines in Fig. 2, thereby effectively preventing their withdrawal from the flue 10 for as long as the bar 16 is in place. In order to withdraw same, it is only necessary to unhook the bar 16 which immediately 10 releases the pipe 12.

I claim:

1. A stovepipe fastener consisting of a pair of yieldable arms secured to one end of a stovepipe extending from the stovepipe inwardly into a flue 20 and a bar hinged to one of said arms and latchable to the other arm for spreading the ends of said arms to a distance greater than the diameter of the pipe.

2. The combination of a stovepipe adapted to 25 be inserted into a flue opening, yieldable arms fastened to one end of said stovepipe and projecting into said flue opening beyond the end of said pipe and a bar disposed between the projecting ends of said arms for bending said yieldable arms 30 outwardly when said pipe is in position.

3. A device of the class described comprising a smoke pipe having projecting from one end thereof on opposite sides of its center a pair of yieldable arms which are attached to said pipe, 35 one of said arms having a perforation near the outer end thereof and the other arm having a bar hinged thereto provided with a hook at its opposite end adapted to engage the perforation in its adjacent yieldable arm.

GEORGE LAFEVER. 40
